UNITED STATES PATENT OFFICE.

HARRY C. ENGFER, OF ROCHESTER, NEW YORK, ASSIGNEE TO DEFIANCE LANTERN
AND STAMPING COMPANY, OF ROCHESTER, NEW YORK, A CORPORATION OF
ONTARIO, CANADA.

LANTERN.

1,113,763.

Specification of Letters Patent.

Patented Oct. 13, 1914.

Application filed December 13, 1912. Serial No. 732,601.

To all whom it may concern:

Be it known that I, HARRY C. ENGFER, of Rochester, in the county of Monroe and State of New York, have invented certain new and useful Improvements in Lanterns; and I do hereby declare the following to be a full, clear, and exact description of the same, reference being had to the accompanying drawings, forming a part of this specification, and to the reference-numerals marked thereon.

My present invention relates to lanterns and it has for its object to provide a simple, cheap and convenient means for mounting the bell of the lantern and for operating the same in an efficient manner toward and from the globe to maintain the latter securely in place on its support or release it therefrom.

20 To these and other ends the invention consists in certain improvements and combinations of parts all as will be hereinafter more fully described, the novel features being pointed out in the claims at the end of the specification.

In the drawings: Figure 1 is a front elevation of a lantern constructed in accordance with and illustrating one embodiment of my invention; Fig. 2 is a side elevation thereof, partly in section, showing the bell raised to release the globe; Fig. 3 is a perspective view of the operating member for the bell and the part on which it is directly mounted, and Fig. 4 is a perspective view of the operating member alone.

Similar reference numerals throughout the several figures indicate the same parts.

I have illustrated my invention, in the present instance, as embodied in a tubular lantern of a familiar type comprising, in general, an oil font 1, burner 2, air chamber 3 and side tubes 4 communicating with the air chamber and in which the bail 5 is journaled.

45 A plate 6 surrounding the burner supports the globe 7 with the assistance of clips 8.

At their upper ends, the tubes 4 lead from a center tube 9 constituting part of a dome indicated generally by 10 and which also comprises a cap 11 and a central inner chimney 12. The latter is provided at its lower end with the usual flange 13 to prevent down draft and is supported by a flange 14 at its upper end that seals the upper end of the tube 9 just beneath the cap 11. A short tube 15 having a perforated flange 16 suitably

secured to the lower end of the tube 9 constitutes an inner collar on the latter that is spaced from the cylindrical walls of the tube 9 though rigid therewith and within this collar slides the upper cylindrical portion 17 of a bell 18 that is guided between the collar and the chimney 12 for vertical movement, to which end its upper extremity is turned inwardly at 18 to provide a bearing against the chimney tube.

The bell 18 performs the usual function, being provided with a flared and beaded portion 19 whereby it may make a tight joint with the shouldered upper rim 20 of the globe 7, and it may be further guided 70 by clips or shoes 21 attached at this point and running on ribs 22 on the tubes 4.

The means I prefer to employ for effecting the up and down movement of the bell between the operative position of Fig. 1 and 75 the inoperative position of Fig. 2 in which the globe 7 is released for removal or lighting purposes, comprises a rotary ring 23 that encircles and slides upon the collar 15 within the tube portion 9 of the dome 10, 80 being confined between the flanged portion 16 thereof and lugs or other suitable devices 24 engaging it from above. The ring may be conveniently formed of a length of wire, one extremity of which is passed through 85 one of the segmental perforations 25 of the flange 16 and fashioned into a loop 26 that constitutes a finger-piece, from which loop proceeds a projection 27 that lies beneath the flange 16 and clear of the dome as a 90 whole. The said projection 27 co-operates with the double cam surfaces constituted by the opposite walls of a slot 28 extending peripherally of the upper cylindrical portion 17 of the bell 18 at an inclination to its 95 axis.

The operation of the device will be readily understood.

If the parts are in the position of Fig. 1, and it is desired to raise the dome, the operating ring 23 is rotated to the left by means of the loop or finger-piece 26 whereupon the projection 27 riding in engagement with the upper cam surface of the slot 28 will raise the bell on its guide to the position of Fig. 2, whereas the reverse movement will lower the parts, and it is to be noted that in the normal or operative position of the bell, as shown in Fig. 1, the operating member 26 lies close against one of the tubes 4 and out 110

of the way. Short shoulders or horizontal portions 29 may be formed at the ends of the slots 28 to lock the projection 27 in a neutral position, while the bell is in either its raised or lowered position.

It will be noted that the open ring 23 is so disposed on the collar 15 that when it is moved to the left to raise the bell 18, which operation imposes more strain on the operating member than does the lowering thereof, due principally to the convergence of the guides or ribs 22, the said ring is rotated in that direction which imparts a tendency for it to contract instead of to open and for the looped end carrying the projection 27 that directly receives the strain to hug the collar 15 closely for support so that disengagement is prevented. The reverse movement causes a tendency for it to pull away but with the lowering of the bell the strain is not great and besides a lug or offset loop 30 may be provided which travels on the opposite side of the slot 25, as shown, to guard against the wire slipping into the slot. By making the ring an open one, it may be readily attached to or detached from its support. To detach it, the operating portion is moved to the extreme right in Fig. 3, and then the adjacent circular portion forced out from the collar 15 as it is slowly returned to the left end of the slot while at the same time the portion of the flange 16 on the outside of the slot is sprung to permit the loop 30 to pass inwardly beneath the lower edge of the collar. The rest of the ring then readily follows through. To apply the ring, a reverse operation is resorted to.

I claim as my invention:

40 1. In a lantern, the combination with a globe support and a dome above the same, of a bell slidably mounted directly on the dome and movable vertically relatively to the dome and a rotary operating member for the bell movable about the dome as a center independently of the connection of the dome and bell.

50 2. In a lantern, the combination with a globe support and a dome above the same, of a bell slidably mounted directly on the bell and movable vertically relatively to the dome, a rotary operating member for the bell movable about the dome as a center and connections between the bell and its operating member comprising a cam surface on one part and a portion on the other coöperating therewith.

3. In a lantern, the combination with a globe support and a dome above the same, of a bell slidably mounted directly on the 60 bell and movable vertically relatively to the dome, a rotary operating member for the bell movable about the dome as a center and connections between the bell and its operating member comprising coextensive cam surfaces on the bell extending peripherally thereof at an inclination to its axis and a projection on the operating member engaging between the surfaces whereby the bell may be moved positively in either direction. 70

4. In a lantern, the combination with a globe support and a dome above the same, of a bell movable vertically toward and from a globe on the support, and provided with a double cam slot extending peripherally thereof at an inclination to its axis and a rotary operating member for the bell formed of a length of wire to comprise a ring slidably encircling a cylindrical portion of the dome, a loop proceeding outwardly 80 therefrom to constitute a finger portion and a free end proceeding from the loop and coöperating with the cam slot.

5. In a lantern, the combination with a globe support and a dome above the same 85 comprising a center tube having an inner offset collar and a central chimney within and spaced from the collar, of a bell slidable vertically on the dome toward and from a globe on the support and guided between a 90 collar and chimney and a rotary operating member for the bell comprising a ring portion encircling and rotatable on the collar.

6. In a lantern, the combination with a 95 globe support and a dome above the same comprising a center tube having an inner offset collar and a central chimney within and spaced from the collar, of a bell slid- 100 able vertically on the dome toward and from a globe on the support and guided between the collar and chimney, said bell being pro- 105 vided with a double cam slot extending peipherally thereof at an inclination to its axis and a rotary operating member for the bell comprising a ring portion encircling and rotatable on the collar, a finger portion, and a projection coöperating with the double cam slot in the bell.

HARRY C. ENGFER.
